UNITED STATES PATENT OFFICE.

ALBERT RÖMER, OF OBERDOLLENDORF-ON-THE-RHINE, GERMANY.

APPARATUS FOR MERCERIZING.

SPECIFICATION forming part of Letters Patent No. 694,109, dated February 25, 1902.

Application filed November 23, 1901. Serial No. 83,399. (No model.)

To all whom it may concern:

Be it known that I, ALBERT RÖMER, a citizen of the German Empire, residing at Oberdolendorf-on-the-Rhine, in the Province of 5 Rhenish Prussia and Kingdom of Prussia, Germany, have invented certain new and useful Improvements in Treating Textile Fiber and Apparatus Used Therein; and I do hereby declare the following to be a full, clear, and 10 exact description of the invention, such as will enable others skilled in the art to which it app pertains to make and use the same.

This invention relates to an improved machine for treating yarn with alkaline lyes and acids, so as to give it a higher brilliancy, as 15 is the case in the so-called "mercerizing" process. It is a known fact that in so treating yarn the fiber must be stretched mechanically to compensate the loss due to shrinkage during the exposure of the yarn to the alkaline lye or acidulous liquid. This stretching has, however, the drawback that by it the 20 yarn gets hard and rough, so that finer numbers become unfit for use as warp for weavings. The yarn also loses in softness and flexibility. Now it is the object of the new machine to avoid these drawbacks in the working of the machines used in mercerizing yarn hitherto, and to attain this the new machine is based upon the principle and upon the 25 experience that a certain amount of power is developed during the shrinking and that this power can be stored and made use of to stretch the yarn again before the deformation and displacement of the cells of the fibers, which 30 has taken place in consequence of the shrinking and after this shrinking action has ceased becomes permanent. Various mechanical equivalent means may be used to carry out 35 this idea into practice, and I do not limit myself, therefore, to the special means shown in the machine described hereinafter, the gist and the principle of the invention being always to store up the power developed by the 40 shrinking—say, for instance, by compressing a spring or by raising a weight in a corresponding manner and then to give out this power again to stretch the yarn as soon as the shrinking action has ceased.

45 On the accompanying drawings, Figure 1 shows a side view of the machine. Fig. 2 is a front elevation of the same seen from the

left of Fig. 1, and Fig. 3 is a plan of the machine.

In the two standards 1 is carried the main 55 shaft 2, to which are keyed the fast and loose driving-pulleys 3 and a pinion 4. This pinion is in gear with a spur-wheel 5 on shaft 6, which is also carried in the frames 1, and said shaft 6 carries a pinion 7, which gears into a 60 wheel 8 on shaft 9, and the wheel 8 is in gear with a pinion 10 on the shaft 11. This shaft 11 is carried by levers 12, movably attached at both sides of the frames 1 upon projections of the shaft 9, and its projections at both sides 65 of the levers 12 form the upper yarn-rollers 13 of polygonal shape. The rearward projection 12^a (to the right in Figs. 1 and 3) of the levers 12 carry adjustable counterweights 14. The wheel 8 also is in gear with a pinion 15 70 on shaft 16, which also has its bearings in the standards 1 and which carries at both ends right and left of the standards the lower yarn-rollers 17. These rollers lie in fixed bearings, they can only rotate, but they are 75 not movable in any other direction. Below them are arranged the troughs 18, containing the alkaline lye or acidulous liquid. They are arranged upon pillars 19, guided vertically in sockets 20. In order to raise 80 and lower the troughs 18, the pillars 19 are supported by rods 21, and these are linked at their lower ends to weighted levers 22, having their fulcrum on a spindle 23, while at their outer ends hand-levers 24 are fixed, by 85 means of which the spindle can be turned, and thus the troughs 18 raised and lowered.

In front of the troughs 18 is arranged upon brackets 25 a long trough 26, and below each yarn-roller 17 is arranged a scoop 27, open at 90 the front end. These scoops are carried upon stilts 28, which are fixed movably upon a rod 29, so that by turning this rod in its bearings 30 the scoops 27 can be moved forward and backward—that is, out of the way of the 95 troughs 18—which are between these and the lower yarn-roller, when the troughs 18 are lowered. There is further arranged below each lower yarn-roller a squeezing or pressing roller 31, carried in the short arms of 100 bell-crank levers 32, the long arms of which are loaded by heavy weights 33. These bell-crank levers 32 have their fulcrum at 34. They press the rollers 31 against the rollers

17, if not hindered by the levers 35, by means of which the weighted lever 32 can be raised, and thus the pressing-rollers 31 pushed away from the yarn-rollers 17.

5 The long rear arms of the lever 12 are suspended on chains 36, which are laid around chain-wheels 37, keyed to a shaft 38, which also carries a worm-wheel 39, and this is in gear with a worm 40 upon a spindle 41, at the front end of which is fixed a hand-wheel 42, by means of which the worm and worm-wheel can be turned and the chains 36 wound on or off the wheels 37 in order to lower or raise the levers 12.

15 In order to be able to adjust and fix the distance between the upper and lower yarn-rollers 10 and 17 for certain lengths of hanks in their natural state, a cross-bar 43 is placed crosswise over the levers 12, and to this cross-bar are connected the racks 44, which hang down sidewise on the frames, as best seen in Fig. 1. A cam or eccentric 45 and a lever 46 press the rack outward and keep it in gear with a fixed counter-rack 47, which is held in a bracket 48 upon the outside of the frames 1. Said eccentric when turned ninety degrees to the one or other side allows the rack 44 to be freed from the engagement with the counter-rack 47, and then it can be moved upward or downward, thereby also allowing the levers 12 to be raised or lowered for a certain fixed minimal distance between the two yarn-rollers 13 and 17.

35 The working of the machine described is as follows: The yarn-rollers 13 and 17 being set for a certain length of hank and the hank put over them, the trough 18, filled with the alkaline lye or acidulous liquid, is raised so much that if now the machine is set in motion the yarn turned around thereby passes through the liquid. The upper roller 13, being made in section in the shape of a polygon, causes the rotation of the yarn. The lever 12 is accordingly loaded by setting the weight 40 14 at the proper place upon the lever 12^a. The yarn then gradually begins to shrink and the upper yarn-roller is pulled down toward the lower one, thereby raising the weighted lever 12^a. The rack 44 has before been freed from 45 the counter-rack 41. This goes on to a certain extent, and when the maximum of shrinkage is attained the rollers and the levers 12 are fixed and held fast in their position. Now 50 the trough 18 is lowered and the scoop 27 is pushed in between the trough and the lower roller 17 and now water is poured over the yarn, so that it is washed out and totally freed from all lye or acid contained therein, and when this is done the rollers are still kept going around and the weight 14 is now allowed 55 to exert its load upon the yarn, so that this now stretches again (an additional weight may be added to that on the levers) until it reaches again its original length, which is determined 60 by the chain 36, the rollers 37, the worm and worm-wheel 39 and 40, and the spindle and hand-wheel 41 42, respectively. The water

65 poured over the yarn for washing it out and during the stretching action is taken up by the scoop 27 and led into the trough 26, whence it is let off by a hole 26^a in the bottom of the same.

Having thus described my invention, I declare that what I claim, and desire to secure by Letters Patent, is—

75 1. In a machine for treating yarn in hanks with alkaline lyes and acidulous liquids, in combination with standards 1 carrying a driving-shaft 2, fast and loose driving-pulleys 3 on said shaft, a pinion 4 gearing into a wheel 80 5 on a shaft 6 also carried in said standards 1, a pinion 7 on said shaft gearing into a wheel 8 on a shaft 9, double-armed levers 12, 12^a fixed movably upon both ends of shaft 9 outside of standards 1, said levers carrying adjustable weights 14 on arms 12^a and a shaft 11 at the ends of arms 12, a pinion 10 on shaft 11 gearing into wheel 8 and polygonal rollers 13 at both ends right and left outside of the standards 1; a shaft 16 carried rotatively on 85 standards 1 below the shaft 11, a pinion 15 on said shaft gearing into wheel 8 and rollers 17 at both ends of shaft 16 below the rollers 13; the whole as described and illustrated and for the purpose set forth.

95 2. In a machine for treating yarn in hanks with alkaline lyes and acidulous liquids standards 1, carrying a driving-shaft 2, a pinion 4 on said shaft gearing into a wheel 5 on a shaft 6, a pinion 7 on said shaft 6 gearing into 100 a wheel 8 on a shaft 9, double-armed levers 12, 12^a held movably upon both ends of shaft 9 outside of standards 1, said levers carrying adjustable weights 14 on arms 12^a and a shaft 11 at the ends of arms 12, a pinion 10 on shaft 105 11 gearing into wheel 8 and polygonal rollers 13 at the end of shaft 11, a shaft 16 carried rotatively on standards 1 a pinion 15 on said shaft gearing into wheel 8 and rollers 17 at both ends of shaft 16 in combination with troughs 110 18 held on pillars 16, said pillars being guided in sockets 20 and made adjustable vertically by counterweighted levers 22 connected to them by rods 26 and a lever 24 fixed to the fulcrum 23 of levers 22; a scoop 27 capable of 115 being pushed in between the rollers 17 and the trough 18 by being held on brackets 28 held pivotally upon a shaft 29, a trough 26 held by brackets 25, the whole as described and illustrated and for the purpose set forth.

120 3. In a machine for treating yarn in hanks with alkaline lyes and acidulous liquids, standards 1, carrying a driving-shaft 2, a pinion 4 on said shaft gearing into a wheel 5 on a shaft 6, a pinion 7 on said shaft 6 gearing 125 into a wheel on a shaft 9, double-armed levers 12, 12^a held movably at both ends of shaft 9, a shaft 11 carried by said levers, a pinion 10 on shaft 11 gearing into wheel 8, rollers 13 at both ends of shaft 11, a shaft 16 carried by 130 standards 1 below shaft 11 rollers 17 at the ends of shaft 11 below rollers 13, a pinion 15 gearing into wheel 8 and thereby turning around shaft 16 and rollers 17 in combination with

pressing-rollers 31 pressed against rollers 17 by a loaded bell-crank lever 32, 33 and capable of being released from pressing against the yarn-rollers 17 by a lever 35 fulcrumed at 35^a 5 in brackets fixed to the standards 1, the whole as described and illustrated and for the purpose set forth.

4. In a machine for treating yarn in hanks with alkaline lyes and acidulous liquids, standards 1 carrying a driving-shaft 2, a pinion 4 on said shaft, a shaft 6 carried by said standards, a wheel 5 on shaft 6 gearing into pinion 4, a pinion 7 on shaft 6 gearing into a wheel 8 on a shaft 9 also carried by said standards 1 a pinion 10 on a shaft 11 gearing into wheel 8, said shaft 11 being carried in weighted levers 12, 12^a having their fulcrum in shaft

9; in combination with chains 36 fixed with one end to the arm 12^a of said levers with the other end to a pulley 37 on a shaft 38, a worm-wheel 39 keyed to said shaft and gearing into a worm 40 on a spindle 41 for turning the worm and worm-wheel by a hand-wheel 42 at the end of spindle 41 for the sake of lowering and raising the weighted lever 12^a the whole 25 as described and illustrated and for the purpose set forth.

In testimony whereof I have affixed my signature in presence of two witnesses.

ALBERT RÖMER.
